UNITED STATES PATENT OFFICE.

WILLIAM EARLEY, OF PHILADELPHIA, PENNSYLVANIA.

PORTABLE HEATER.

SPECIFICATION forming part of Letters Patent No. 408,469, dated August 6, 1889.

Application filed August 22, 1888. Serial No. 283,418. (No model.)

To all whom it may concern:

Be it known that I, WILLIAM EARLEY, a citizen of the United States, residing at Philadelphia, in the county of Philadelphia and State 5 of Pennsylvania, have invented certain new and useful Improvements in Portable Heaters; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention has relation to portable heaters, and has for its object the provision of a heater of novel form and construction, wherein a greater area of radiating-surface is exposed to the air passing through the air-heating 20 space of the furnace than in heaters of the ordinary construction, and without increasing the capacity of the fire-box or the consumption of fuel.

25 Heretofore in heaters of the above class the products of combustion have in some cases been caused to pass directly from the fire-box to the chimney, while in others said products pass through a series of vertical or horizontal drums arranged within a suitable air-chamber, the air therein passing directly from its 30 inlet to its outlet before it becomes thoroughly heated.

In carrying my invention into effect I employ a series of horizontal drums or pipes so arranged relatively to the fire-box of the heater and the chimney that the products of combustion will pass to and fro on both sides of the fire-box from a point in the rear of the same to a point in front or in a line with the front of 40 the fire-box, and will descend from one such horizontal drum or pipe to the one next below, thus traveling in an opposite direction to the direction of the incoming cold air.

In addition to the horizontal drums or pipes 45 arranged as above described, I provide a series of horizontal metallic partitions so arranged between adjacent drums as to divide the air-space of the heater into a number of horizontal passages communicating with each 50 other at alternate ends, so that the incoming cold air will be caused to follow a sinuous path around and with said drums, thus thor-

oughly heating the air before it reaches the flues and effecting a great saving in the quantity of fuel consumed, and to travel in opposite direction to the outgoing products of combustion.

55 My invention consists in the novel arrangement of the pipes or drums for conveying the products of combustion from the fire-box to the chimney, in the novel construction and arrangement of the flues or passages for conveying the incoming cold air through the air-space, and in the novel construction, combination, and arrangement of parts hereinafter 60 described and specifically claimed.

Referring to the accompanying drawings, Figure 1 is a perspective view of my improved portable heater with a portion of the exterior casing broken away and one of the horizontal partitions of the air-space removed to show the arrangement of the smoke-pipes, and Fig. 2 a vertical longitudinal sectional view of the same.

70 As shown in the drawings, the heater-casing is in the form of a parallelogram, for the reason that it permits of the proper arrangement of pipes and flues necessary to the accomplishment of the objects of my invention within a comparatively small space.

75 A designates the base of the heater, consisting of a cast-iron frame with sheet-iron sides and ends and having a suitable air-inlet a and ash-pan door a'.

80 B designates the fire-box, comprising a cylindrical metallic shell lined with fire-brick and provided with the usual grate, ash-box, &c.

C designates the exterior casing of the heater, conforming in shape to the base A and provided with the dome C' and hot-air flues C² 90 C³ C⁴.

The fire-box B is arranged as closely as may be convenient to one end of the casing, and having extending from near the top and at the rear of the same a horizontal smoke-pipe 95 D, that is divided near its rear end by a vertical partition d. Upon each side and near the rear end of pipe D are laterally and downwardly projecting pipes E E, jointed to horizontal pipes F F, that extend forward to or 100 nearly to the front of the heater, passing between the fire-box B and the exterior casing C.

At their forward ends the pipes F F com-

municate, by short vertical pipes G G, with horizontal pipes H H, which extend from the front to near the end of the casing C, parallel with and of the same length as pipe E, and 5 are connected by a horizontal pipe I at right angles therewith, and having at its center a vertical pipe K, with a horizontal connection L, leading out through the casing C to the chimney. The direction of travel of the 10 products of combustion through the pipes D E E F F G G H H I K to the chimney is indicated by the arrows therefor in dotted lines. The object of the vertical partition d in the 15 pipe D is to divide the products of combustion as evenly as possible between the pipes on each side of the fire-box.

The base A is surrounded by a plate A', having ports a² a² near the front of the 20 heater for the admission of air which has become partially heated in its passage through the base and between the grate and ash-pan. Parallel with the plate A', I arrange a sheet-metal partition M, which extends over the 25 pipes H H from the front of the exterior casing C almost to the back of the same, leaving a space m between the rear edge of said partition and said casing for the passage of the air into the next-above space, said partition also being formed with suitable holes for the 30 passage of the vertical pipes G G K and the fire-box B.

Above the horizontal pipes F F is arranged a second horizontal partition M', that extends from the rear of the exterior casing almost to 35 the front of the same, leaving a space m' similar to space m between the front edge of this partition and said casing, allowing of the passage of the now hot air into the dome C'. Said partition M' also is formed with holes for 40 the passage of the fire-box B and the slanting pipes E E.

The horizontal partitions M M', in connection with the plate A' and the dome C' of the heater, divide the air-space of the heater into 45 horizontal flues communicating with each other at alternate ends, and through which the air follows a sinuous path in opposite directions to the products of combustion and all the while in contact with the pipes through 50 which the latter is conveyed.

The direction of travel of the products of

combustion, as before suggested, is indicated by dotted arrows in the drawings, while that of the air-currents is indicated by full arrows. By the employment of the horizontal 55 smoke-pipe and the horizontal partitions I claim that within the same cubical space a much larger extent of effective radiating-surface is obtainable than where the smoke or combustion flues are constructed and arranged as in the ordinary manner—that is, in a vertical position and without the horizontal partitions which I employ.

While I have shown and described but two sets of horizontal pipes F F G G and but two 60 horizontal partitions M M', it is obviously within the spirit of my invention to increase the numbers of pipes and partitions, if found necessary or expedient; but I prefer the arrangement specifically shown and described. 65

I am aware that a heater has heretofore been constructed with a chamber at the rear of the fire-box divided by an S or similarly-shaped sheet of metal secured to the sides of 70 said chamber into two broad and shallow tortuous heat and air passages of similar curvature, and having in their concavities shelves secured to said sides. Therefore I do not wish to be understood as claiming, broadly, such a construction; but

What I do claim, and desire to secure by Letters Patent, is—

In a portable heater, the combination, with the fire-box B in the casing C, having the dome C', with hot-air outlets, mounted on the 85 base A, with the cold-air inlet a, of the pipe D, with the partition d therein, leading from the rear of said fire-box and communicating with the branches E E of the pipes F F, which pipes communicate with the branches G G of the pipes H H, which latter communicate with the smoke-outlet L through the pipe I and its branch K, the plate A', mounted on the base A, and the plates M M', sustained in the casing C, having the inlets a², m, and m' at alternate ends, as and for the purpose described. 90

In testimony whereof I affix my signature in presence of two witnesses.

WILLIAM EARLEY.
